LINOLEUM OR SIMILAR ARTICLE

Alex Steinweiss, Atlantic Beach, N. Y., assignor to Fibre-board Paper Products Corporation, San Francisco, Calif., a corporation of Delaware

Application February 18, 1958, Serial No. 49,694

Term of patent 14 years

(Cl. D92—17)

The figure is a plan view of a piece of linoleum showing my design. The broken lines outline a design unit which is repeated in regular succession as indicated by the extensions beyond the boundaries of such unit.

I claim:

The ornamental design for a linoleum or similar article, substantially as shown and described.
